UNITED STATES PATENT OFFICE.

CARL GUGGENBUEHLER, OF NEWARK, NEW JERSEY, ASSIGNOR TO JEAN V. LUTZ, OF NEW YORK, N. Y.

BABBITTING TOOL OR MOLD.

1,271,310.

Specification of Letters Patent.

Patented July 2, 1918.

Application filed December 8, 1917. Serial No. 206,320.

To all whom it may concern:

Be it known that I, CARL GUGGENBUEHLER, a citizen of the Empire of Germany, residing at Newark, in the county of Essex and 5 State of New Jersey, have invented certain new and useful Improvements in Babbittting Tools or Molds, of which the following is a specification.

The present invention relates to means 10 for facilitating the casting of liners of brass or babbitt onto so called truck boxes or driving boxes of axle bearings for locomotives or the like, which liners usually are employed to fill the gap or space between 15 the hub of a wheel and the bearing box.

According to the hitherto used process of applying such liners, the box is clamped in a planing machine and the liner which has been first cast into the proper shape is 20 screwed to the box and then planed off to the desired thickness. Such method obviously renders the work more or less complicated requiring separate men for casting and planing the liner. There is also much waste 25 of material occasioned by this method as the scrapings of the expensive metal falling to the ground mix with dust and other materials and require additional labor to separate them if it is desired to recuperate the metal. 30 The recuperated metal when heated again loses its resisting power and becomes practically valueless.

The object of my invention is therefore to do away with these drawbacks and to provide means whereby much labor can be 35 saved and waste avoided. This is accomplished by providing a tool which can be easily clamped or otherwise removably applied to the hub end of the bearing and 40 which will form a sort of mold to receive the material cast and to form the liner at once of the desired thickness and size, dispensing with any subsequent finishing work.

With some bearings particularly those 45 known as driving wheel boxes and which apart from the hub liner also have inner liners the device employed must be somewhat modified as the thicknesses of the inner liner vary according to wear. It is therefore 50 another object of my invention to provide means which enable the device to be adjusted according to the particular size of the inner liners of such boxes.

My invention also consists in the construction, arrangement and combination of 55

parts as will be hereinafter more fully described and set forth in the appended claims.

Reference is had to the accompanying drawing in which similar reference characters denote corresponding parts and in which Figure 1 is a sectional bottom view of a truck box and of my device applied to the hub end thereof showing the liner cast onto said end; Fig. 2 is a section on line 2—2 of 60 Fig. 1 showing the truck box lying on its side with the device applied to the hub end thereof and the metal liner cast onto it; Fig. 3 is a top plan view of the device proper; Fig. 4 is a bottom plan view thereof; and 65 Fig. 5 is a perspective view of a truck box with the liner cast onto its hub end.

Referring in detail to the drawing 10 denotes an ordinary truck box such as used on bearings of locomotive axles, the hub 75 end of which is to be provided with a liner 10' of brass or babbitt. To facilitate the casting of the said liner I provide a tool forming the subject of my invention.

The tool comprises an iron or steel plate 80 12 of substantially rectangular shape and corresponding in size with that of the end faces of the box and preferably composed of two superposed layers or sections 12', 12" 85 removably joined together by screws 13 or otherwise for the purpose hereinafter to be mentioned. The upper section 12' is provided on its outer face with two upwardly projecting and laterally slanting loops or handles 14 which as in the example shown 90 may be made of a single piece of material (Fig. 3). It also is provided with lateral offset marginal flanges 15 of which four are shown in the drawing (Fig. 3). Supported in these flanges on each side of the box is 95 a clamping mechanism composed of lateral bars 16 having each two screw bolts 17 projecting upwardly therefrom near each end thereof and adapted to pass through perforations in the said flanges. The screw bolts carry each at their upper ends nuts 19 between which and the flanges are mounted spiral springs 20. The clamping bars 16 are adapted to engage the under surfaces of the flanges 10" of the box at the hub end of 105 the latter and on the tightening of the springs 20 to clamp the plate 12 in position on the said hub end of the box. The sections 12', 12" 110 have their inner faces planed to form even

and smooth surfaces. Projecting centrally from the inner section 12² is a flange 21 substantially of U-shaped configuration to correspond in shape and size with and to snugly fit in the hollow 10³ of the box 10. Around the flange 21 the inner section 12² has a recess 22 as shown in Fig. 4, which in form and size corresponds with those of the liner to be cast. The flange 21 when the tool is applied is adapted to enter the hollow 10³ and the inner surface of the section 12² is adapted to rest evenly on the surface of the hub end of the box with the recess 22 surrounding the top and sides of the flange 21 forming thus a mold into which the brass or babbitt is cast to form the liner 10'. An opening 10⁴ provided in the upper section and leading into the recess 22 serves as a charge opening for the molten metal. Working in threaded openings provided in the plate 12 are four pressure screws 24 which project upwardly and normally are screwed outwardly so that their inner ends do not protrude below the inner surface of the section 12'. When the metal has been cast and it is desired to remove the tool from the box the screws 24 are screwed inwardly to press against the body of the box and to lift the plate therefrom against the tension of the clamping springs 20.

It will be seen that by means of this device the liner can be easily and readily cast onto the box without any waste of material and without requiring subsequent finishing work such as planing or the like as is required with the old process. The material cast into the hole or recess 22 is evenly distributed around the edges of the hollow 10³ of the box to a thickness and width which is determined by the thickness of the inner section of the plate and the size of the recess 22 provided in the inner section. The bottom of the upper section 12' which covers the opening or recess 22 being also even and smooth will produce a finished smooth surface of the liner so that no subsequent work will be required.

The thickness of the liner or its width or both may be varied according to requirements and this can be done by simply exchanging the lower section of the plate for another of a greater or smaller width and with a larger or smaller recess as the case may be. To this end the plate 12 is made of two layers removably connected together by the screws 13 as has been described. Or the thickness of the liner cast may be varied by loosening the screws which connect the two layers of the plate 12 so as to permit them to be separated slightly from each other.

Since the construction can be modified in many other ways without departing from the spirit of my invention I do not wish to limit myself to the details described and shown.

What I claim and desire to secure by Letters Patent is:

1. A tool for facilitating the casting of hub liners on bearing boxes, comprising a plate having on its lower face a recess closed at its top and a flange projecting centrally from said lower face and adapted to fit in the hollow of the box, the parts of the lower face of said plate outside of said recess being even and adapted to rest evenly on the surface of the hub and of the box, and the space formed between the walls of the recess, the top surface of the box and the circumference of the flange being adapted to constitute the mold. 80

2. A tool for facilitating the casting of hub liners on bearing boxes, comprising a plate composed of two superposed sections removably joined together, the inner section being formed with a flange projection centrally therefrom and having a recess surrounding said flange, said flange being adapted to snugly fit in the hollow of the bearing box and in coöperation with said recess to form a mold. 90

3. A tool for facilitating the casting of hub liners on bearing boxes, comprising a plate composed of two superposed sections removably joined together, the inner section having a central flange, and a recess around said flange which when the tool is applied to the bearing box is adapted, in coöperation with said flange, to form a mold, and means on said plate for clamping said tool to the bearing box. 95

4. A tool for facilitating the casting of hub liners on bearing boxes, comprising a plate having a flange of substantially U-shaped configuration projecting centrally therefrom, and a recess around said flange and of a shape and size to correspond with those of the liner to be cast, said flange being adapted to snugly fit into the hollow of the box and in coöperation with said recess to form a mold for said liner. 105

5. In combination with a bearing box for locomotives or the like, of a tool for casting a hub liner thereon and comprising a plate made of two superposed layers or sections removably connected together and forming smooth and even bottom surfaces, the bottom section having a recess forming a mold to receive the molten metal and form said liner and the upper section being perforated to allow of the molten metal being charged into said mold, and means on said outer section for removably fastening said plate to said box. 115

6. The combination with a bearing box for locomotives or the like, of a tool for facilitating the casting of a hub liner thereon and comprising a plate having a recess, a member on said plate adapted to engage and snugly fit in the hollow of the box and in coöperation with said recess to form a mold 125 130

to form the said liner and means for removably fastening said plate to said box.

7. A tool for facilitating the casting of hub liners on bearing boxes comprising, a 5 plate composed of a plurality of superposed sections, one of said plates having a recess, and means on one of said plates adapted to engage and snugly fit in the hollow of the box and in coöperation with said recess form

a mold for said liner, said plates being ad- 10 justably secured together whereby liners of different thicknesses may be cast.

In testimony whereof I affix my signature in presence of two witnesses.

CARL GUGGENBUEHLER.
